UNITED STATES PATENT OFFICE

JOHN DALE KEENAN AND EMIL FIGGE, OF NEW YORK, N. Y., ASSIGNEES TO AMERICAN STEEL CHASE CO., INC., OF NEW YORK, N. Y., A CORPORATION OF NEW YORK

POWER CUTTING MACHINE FOR PRINTERS' BORDERS

Application filed May 11, 1929. Serial No. 382,444.

This invention relates to apparatus for mitering printers' rules.

Such rules are invariably type high, or 0.918 inches in height, from 1 to 24 points (0.0138" to .2484) in thickness, and up to 2 feet in length, the material being soft brass or hard type metal, the same being used to produce borders, breaks and ornamental linings in printed matter.

Up to the development of the present machine, practically all rule mitering was performed by hand operated devices, slow, laborious and depending for accuracy on the workman, requiring considerable time and skill, as two separate operations were required, first cutting the rule to proper length and then mitering its ends.

Having these disadvantages in mind it has been an object of the present invention to provide a machine that cuts and miters rules by power at one operation, in a fundamentally correct manner, clamping the rule, irrespective of its thickness in a positively secure manner, in an upright position, at two points closely adjacent and on opposite sides of an accurately bevelled, double faced cutter movable in a vertical plane across the face of the work part.

A further feature is in the provision of a machine in which the cutting and mitering operation is done at a single stroke, rendering it necessary to use two clamp jaws for clasping the work and holding each of the severed pieces rigid after the combined cutting and mitering operation has been performed.

Another purpose is to produce a machine consisting of a complete unit, electrically driven, and provided with all desirable adjustments, both for the cutter and for the rule, so that a border or a panel can be cut and mitered to any given length at one operation.

These and other important features, which will hereinafter appear as the description progresses are accomplished by the novel and practical design, construction and combination of parts hereinafter described and illustrated in the accompanying drawings, con-

stituting a material part of this disclosure, and in which:—

Figure 1 is a top plan view of a machine made in accordance with the invention.

Figure 2 is a side elevational view of the same.

Figure 3 is an enlarged, fragmentary detail showing the clamping mechanism.

Figure 4 is a fragmentary, sectional view taken on line 4—4 of Figure 3.

Figure 5 is a transverse sectional view taken on the line 5—5 of Figure 3.

Figure 6 is a similar sectional view taken on the line 6—6 of Figure 2.

Referring in greater detail to the drawings the numeral 5 designates a platform on which a motor supporting block 6 and electric motor 7 are mounted. In front of and offset on the platform there is provided a stationary base 8 having a front cross head 9 somewhat greater in height than the rear portion 10 of the base.

The upper face 11 of the base is formed with a dove-tailed groove 12 in which the correspondingly shaped bottom 13 of an angular upright bracket 14 having reinforcing ribs 14a, is adjustably positioned as shown by Figures 2 and 6 of the drawings.

An adjusting screw 15, passing through a plate 16 at the rear of the base 10, engages the bracket 14 whereby it may be adjusted to take up any appreciable wear on the cutter, further to be described. The bracket may be held rigidly to the base by means of clamp screws 17.

A forwardly projecting face of the bracket cooperates with a grooved spindle head 19, movable in a vertical plane by an operating lever 20, the lever being pivotally connected as at 21, to an arm 22 carried by the bracket and pivotally connected, as at 23, to a link 24 pivoted to the top of the bracket, and a gib 24a is provided to take up the wear on the surface of the spindle head.

The inner end of the lever 20 is equipped with lateral arms 21a and a pair of tension springs 22 is fastened to the arms and to hooks 23 on the base of the bracket to normally maintain the operating lever and the

- spindle head in a raised position, see Fig. 1 and 2, is positioned to receive the cuttings. The spindle head 19 is formed with spaced bearings to carry a spindle 25 and between the bearings is a pulley 26 over which is trained a belt 27 driven by the motor shaft pulley 28, the bracket and the spindle head being cut away, as at 29, 30, for the passage of the belt.
- 10 In this connection, it will be noted that the motor shaft 31 is in a plane slightly below the spindle 25 so that there is tension on the belt when the spindle head is in its top or bottom position, thus preventing the belt from slipping. The spindle is equipped with a toothed cutter 32, preferably of high speed steel, and is secured on the spindle by a nut 33. This cutter, as shown, is accurately bevelled on both sides to an angle of 90 degrees, thereby producing mitered cuts in the work parts.
- 15 The bracket 14 carrying the spindle head is so adjusted that the cutter 32 may be brought into engagement with the rule to be cut when the lever is depressed. By referring to Figure 4 it will be noted that the cross head 9 is equipped with a work supporting plate or strip 34 having a notch or recess 35 on which the rule 36 to be cut is positioned, as shown in dotted lines.
- 20 On the plate 34, abutting the inner wall of the cross head, there is positioned a replaceable lead or soft brass plate 37 to protect the metal cross head from the cutter.
- 25 The rule 36 to be mitered is clamped and held firmly in position to be operated upon by the rotary cutter by a double jawed clamp 40 which may be adjusted to accommodate rules of varying thickness; this clamp consists of a forked block 38 slidable in a recess 39 cut in the cross head 9, below the top thereof, and preferably integral with the block are a pair of upwardly extending clamping jaws 40, 41, spaced so that the cutter 32 may be operated without interference.
- 30 The adjustment and locking means for the movable jaws consist of a threaded shank 42 on the block 38, its shank extending through the front wall of the cross head 9.
- 35 A collar 43 fastened to the cross head 9 and an internally threaded sleeve 44 having a knurled knob 45 provides means for adjusting the clamping jaws to engage the work to be cut, as shown in Figures 3 and 4.
- 40 In the detail shown by Figure 5 where the clamping jaws are in their released or unlocked position, means are provided for dislodging the finished work, consisting of a releasing pin 46 having a spring 47, the pin passing through a hole in a platen or bar 48 which carries an adjustable gage 49. By pressing the pin against the resistance of the spring, the rule may be released and caused to drop into a discharge chute 50, while a receptacle 51, shown in dotted lines in Figures
- 45 The operation of the machine will now be briefly described. The knob 45 is first rotated and the clamp jaws moved inwardly as shown in Figure 5. A rule is then placed in an edgewise position against the strip 37; a reverse movement of the knob causes the clamp jaws to grip and engage the work. The operator then depresses the lever handle 20 against the resistance of the springs, bringing the spindle head and the cutter downwardly across the face of the rule. As the lever handle is released, the spindle head rises by reason of the springs 22a, being limited in its movement by a stop 52.
- 50 While herein is shown and described the invention, it will be understood that modifications and changes may be resorted to. Therefore the invention is not to be limited and restricted to the exact details shown and described but such changes and modifications may be made as may fairly fall within the scope of the subject matter claimed.
- 55 Having shown and described the invention, what is claimed as new and desired to secure by Letters Patent, is:—
1. A machine for simultaneously cutting and mitering a printer's border rule comprising a base having a work support, a bracket adjustable on the support, a spindle head 95 slidable on the front of the bracket, a shaft having a double bevelled toothed cutter on the spindle head, a hand lever connected to the bracket and spindle head for moving the cutter vertically with respect to the side of rule, a forked clamping member on the front of the work support for engaging the inner side of the rule adjacent each side of said cutter, and manually actuatable means to dislodge the rule after mitering. 100
2. A machine for simultaneously cutting and mitering a printer's border rule comprising, in combination, a base having a work support, a raised bracket horizontally adjustable on the support relative to its front edge, a spindle head 105 slidable vertically on the front of the bracket, a shaft having a double bevelled toothed cutter in the spindle head, a hand lever connected to the bracket and spindle head for moving the cutter vertically with respect to the side of a rule, an adjustable clamp block having a threaded shank, and a knob having a threaded hub to engage said shank, said block having upwardly and inwardly extending work engaging jaws between which said cutter operates whereby when the rule has been cut and mitered the separate parts will be retained in positive position by the respective clamping members 110 of said jaws. 120
3. A machine for simultaneously cutting and mitering a printer's border rule comprising, in combination, a base having a work support, an upright bracket on said support, a dove tailed spaced bearing block 125 slidable

on the front face of said bracket, a spindle journalled in the bearings of said block, said spindle having a driver pulley between the bearings and a double bevelled toothed cutter on its projecting end, a manually operable lever connected to the bracket and block to raise and lower the cutter, an adjustable clamp block having a threaded shank, a knob having a threaded hub to engage said shank, said clamp block having upwardly and inwardly extending work engaging jaws between which said cutter operates whereby when the rule has been cut and mitered the separate parts will be retained in positive position by the respective cleamping members of said jaws, and means to adjust the vertical path of said cutter relative to said clamp block.

4. A machine for simultaneously cutting and mitering a printer's border rule comprising, in combination, a base having a work support, an upright bracket on said support, a spaced bearing block slidable on the front face of said bracket, a spindle journalled in the bearings of said block, a pulley for driving said spindle, a double bevelled toothed cutter mounted on said spindle, a manually operable lever connected to the bracket and block to raise and lower the cutter, an adjustable clamp block having a threaded shank, a knob having a threaded hub to engage said shank, said clamp block having upwardly and inwardly extending work engaging jaws between which said cutter operates whereby when the rule has been cut and mitered the separate parts will be retained in positive position by the respective clamping members of said jaws, and means to adjust the vertical path of said cutter relative to said clamp block.

40 In testimony whereof we affix our signatures.

JOHN DALE KEENAN.
EMIL FIGGE.
